UNITED STATES PATENT OFFICE.

EDWARD CHESHIRE, OF CLEVELAND, OHIO, ASSIGNOR TO THE WHITE SEWING MACHINE COMPANY, OF CLEVELAND, OHIO, A CORPORATION OF OHIO.

MAIL-MARKING MACHINE.

SPECIFICATION forming part of Letters Patent No. 690,696, dated January 7, 1902.

Application filed February 5, 1900. Serial No. 4,089. (No model.)

To all whom it may concern:

Be it known that I, EDWARD CHESHIRE, a citizen of the United States, residing at Cleveland, in the county of Cuyahoga and State of Ohio, have invented a certain new and useful Improvement in Mail-Marking Machines, of which the following is a full, clear, and exact description, reference being had to the accompanying drawings.

10 The object of the invention is to provide a machine of a simple and inexpensive character which shall be capable of rapidly applying postmarks to letters, postal cards, and analogous mail-matter and of canceling the 15 stamps thereon, and of finally effecting an orderly rearrangement of the marked letters in an easily-handled pack.

In the machine shown embodying my invention a pack of mail-matter, which may be 20 made up of letters, postal cards, &c., is placed on edge upon a table, down which it is moved toward the marking and segregating devices. A pneumatic marking device applies the 25 mark to the foremost letter in the pack. A bending device takes hold of the lower edge of this letter and bends it away from the pack. The partial segregation of this letter is made 30 complete and permanent by appropriate mechanism, consisting, as shown, of certain movable fingers which take hold of the bent lower edge of this letter. The bending device releases its hold upon the letter and moves out of the way, and the letter is then through 35 the movement of said fingers withdrawn from the pack and added to a pack of marked letters on a suitable supporting-table.

The invention consists in the combination of parts for effecting the several results referred to both separately and in proper sequence, as well as in the more specific combinations of parts constituting the particular machine in which the invention is embodied, all of which will be pointed out definitely in the claims.

45 In the drawings, Figure 1 is a plan view of said machine. Fig. 2 is a rear elevation thereof. Fig. 3 is a front elevation of the machine and some parts of the supporting-framework broken away, and a part of the two 50 tables which respectively support the un-

marked and marked letters are also broken away. Fig. 4 is a sectional front elevation of the machine, the section being taken in the plane indicated by the line 4 4 of Fig. 5. Fig. 5 is a sectional side elevation on the left side of Fig. 3 when the two tables have been removed. Fig. 6 is a sectional plan view in the plane indicated by line 6 6 of Fig. 4. Figs. 7, 8, and 9 are respectively views of certain disks having cams and cam-grooves 60 which operate various parts of the mechanism. Figs. 10 and 11 are enlarged views showing the marking device, the bending device, and the segregating device. Fig. 12 is a plan view of a rocking frame which carries the 65 needles. Fig. 13 is an enlarged side view of one of the needles, the block which carries it, and the end of the arm to which said block is attached. Fig. 14 is a sectional view of a part of the pneumatic marking device. Fig. 70 15 is a vertical section through the intake-opening of the pump. Fig. 16 is a vertical section through the pump on line 16 16 of Fig. 1. Fig. 17 is a sectional side view of the table.

The pack of unmarked letters 1 is placed upon a slightly-inclined table 2. The letters rest upside down upon their edges, with their stamped and addressed faces presented to the marking device, which is adjacent to the 80 lower end of said table. One side of all of said letters bears against a guide-bar 2^a, and the pack of letters is held in the compact bunch by means of a follower 2^b, which rests against the rearmost letter in the pack and 85 helps to push the entire pack down the table as the letters are removed from the front end of said pack. This follower is a metal block mounted on wheels 2^c, and the force of gravity is relied upon to move it. To facilitate 90 the movement of the pack down the table, two bars 2^d are set into longitudinal grooves in the top of said table. These bars project slightly above the top of the table, and the letters rest upon them. During the operation of the machine these bars are caused to oscillate longitudinally, and this movement assists the follower in moving said letters. The upper part of the foremost letter in the 95 unmarked pack rests against a plate 3^a, which 100

faces said pack and forms a part of the framework which supports the movable mechanism. The upper part of the pack of letters is therefore clamped lightly between this plate 3^a 5 and the follower. The lower part of the pack is not so held, and therefore the lower edge of the foremost letter may be bent across the lower edge of said plate 3^a, away from the other letters. The lower edges of the other 10 letters are prevented from following this bent letter by means of the pins 4, which are periodically projected up through the table. These pins may either pass between the letters or penetrate the lower edge thereof, as 15 the case may be.

The stamp is canceled and the postmark applied to the foremost letter in the pack by means of a pneumatic marking device. This consists, essentially, of a block 5, having a 20 recess 5^a in its front face, and a plate 5^b, secured to lugs 5^c in said recess, which plate carries on its outer face the appropriate marks and characters. This plate is not quite so large as the recess in which it is set, 25 wherefore air may be drawn around its edges into said recess. The block has trunnions 5^d on its ends, one of which is tubular and communicates with the recess. The outer end of this tubular trunnion is connected by a flexible pipe 6^a with an air-pump 6, by means of which periodically a partial vacuum is created in said recess. This block is mounted, 30 by means of these two trunnions, in the lower ends of two depending arms 7^a, which are made fast to a rock-shaft 7. An arm 7^c is made fast to this rock-shaft, and a push-rod 7^d is pivotally connected to this arm. The lower end of this push-rod is forked and straddles the main shaft 10, and on its side it has a pin 7^e, 35 which enters a cam-groove 12^a in the face of a disk 12, secured to said shaft. During the operation of this machine this shaft is constantly rotating, with the result of moving this push-rod in a substantially endwise direction, which movement causes the arms 7^a, 40 carrying the marking device, to be rocked, so as to move the marking device toward the package of letters and then away from them. On the rear side of this block 5 is a tail 5^e, 45 carrying a friction-roller 5^f, which roller is adapted to bear upon a curved track 3^b, formed on the rear upright member 3 of the frame. This track has what may be called a "notch" 3^c extending downward about midway between its ends. A rod 5^g is pivotally connected with the tail of this marking-block, and it passes through a bracket 3^d. A spring 5^h embraces the rod and thrusts endwise against said bracket and a nut 5^k on the lower 50 end of the rod. Consequently this spring acts to draw the tail of said printing-block downward and to hold the friction-roller 5^f against said track. When, therefore, the block 5 is swung away from the pack of letters, the tail thereof moves down into this notch, whereby the printing-face of the block is turned upward. A further movement of

the rocking frame carries this block so that its printing-face engages with an inking-belt 8. This belt runs over two rollers 8^a 8^b and 70 passes beneath an anvil 8^c, which is directly over the part thereof with which the printing-plate engages. The belt thereafter is held firmly when the printing-plate is pressed against it and receives therefrom an even supply of ink. One of these rollers is turned step by step by mechanism to be presently described, so that a new part of this belt is constantly presented to the action of the printing-plate. The belt is supplied with ink from 80 an inking-roller 8^d, which contacts with it, and this inking-roller is supplied with ink when necessary by means of a supply-roller 8^e, mounted on a swinging frame 8^f and dipping into the ink, the ink being held in a well 85 8^g, secured to the upper part of the frame members. The operator must occasionally take hold of the arm 8^h and cause this swinging frame to rock, so as to carry said supply-roller into contact with the inking-roller, 90 whereby it is supplied with ink, which is in turn supplied to the inking-belt.

After the printing-plate has been inked in the manner described the swinging frame reverses its movement and carries the printing-block toward the unmarked pack of letters. Said printing-block is turned upon its trunnions by means of the described mechanism, and its printing-face is carried close and parallel to the foremost letter in the pack. At 100 this instant the air-pump 40 operates to withdraw air from the recess in said printing-block, wherefore the foremost letter is pressed with sufficient force against the printing-plate, and thereby the stamp is canceled and 105 the postmark applied. At approximately the same instant a plurality of needles 9 are moved upward and are caused to penetrate the lower edge of the foremost letter. A valve in the air-pump is then opened and 110 air permitted to rush into the partial vacuum in said printing-block, whereby the letter is released. These needles are secured with their points upward to certain blocks 9^a, which are beveled on that side of their upper ends 115 which faces the letters. These needles are placed a short distance from this beveled surface, the distance being less than the thickness of the thinnest piece of mail-matter which the machine is designed to mark—namely, a 120 postal card. These blocks are pivotally connected to the free ends of certain arms 13^a, and springs 9^b act to swing said blocks toward the package of letters, although there are stops 13^b that limit the extent of such movement. The arms to which the blocks are pivoted are moved up and down and toward and 125 from the pack of letters by appropriate mechanism, which will be presently described. When the arms are moved upward, the beveled surfaces of this block strike the lower edge of the foremost letter, whereby the blocks are caused to swing backward in opposition to their springs a greater or less distance, de- 130

pending upon the thickness of the letter, wherefore the needles when moved up will penetrate the lower edge of the postal card or letter, whether it be thick or thin. The blocks 5 and needles are then moved away from the pack of letters by the arms 13^a, and this causes said foremost letter to bend over the lower edge of the plate 3^a, against which the upper part of said letter is held, substantially 10 as shown in Fig. 10. At this instant the lower edge of the letter is grasped between vertically-movable fingers and the needles are moved down and withdrawn from the letter, and then the arms 13^a, which carry the blocks 15 and needles, are moved still farther to the left and from beneath said letter. The fingers which have taken hold of the letter then move downward, carrying the letter with them, until 15 said letter reaches substantially the level of 20 the table, when the letter is released.

The described movements of the needles and the arms which carry them are produced in the following manner: Four of the arms 13^a are part of a frame 13, which is loosely 25 mounted on a rod 14, which extends between and is secured to the lower ends of the arms 14^a to form another swinging frame. The frame 13 has a rearwardly-extended arm 13^c, and a pin 13^d on said arm enters a cam-groove 31^a in the disk 31, attached to the main shaft 10. This cam-groove causes the said frame 13 to rock upon its pivot, thereby giving to the needles the up-and-down motion. The arms 14^a are loosely hung on the axis of a 30 roller 8^a, and one of these arms has an extension 14^b, with a lateral extended pin 14^c, which engages with cam-groove 31^b on the disk 31, wherefore this frame is rocked, and thus 35 gives the forward-and-backward movement 40 to the frame 13, which carries the needles. The mechanism just described constitutes what I term the "bending" mechanism—that is, the mechanism by which the lower edge of the letter is bent away from the rest of the 45 pack into a position to be grasped by the segregating-fingers. These segregating-fingers 15^a 15^b are carried by a vertically-movable head 15, which is guided upon a fixed vertical standard 16. Of each pair of fingers 50 one, 15^a, is fixed to the head, and one, 15^b, is movable. All of the movable fingers are fixed to a rock-shaft 15^c, mounted in said head, and a spring or springs 15^d act to close said movable fingers against the fixed fingers. An 55 arm 15^e is secured to this rock-shaft, however, and it carries a friction-roller 15^f, which engages with the face of a rocking block 17, pivoted about midway between its upper and lower ends. This block has a tail 17^a, having a laterally-extended pin 17^b, which engages with a cam-groove 30^a in the disk 30, which is fast to shaft 10. When the head 15 is near the top of its path of movement, this block 17 is rocked, with the result of so rocking the rock-shaft 15^c that the fingers are 60 opened. When the aforesaid head is about to descend, this block rocks in the opposite

direction far enough to allow the fingers to be closed by their springs. When the head is near its lower position, the block again 70 rocks against the roller 15^f, whereby the rock-shaft 15^c is rocked and the fingers are opened. The head 15 goes down a little farther, leaving the latter on the table 18, and then this block 17 rocks in the other direction and allows the fingers to close. The head 15, which carries the segregating-fingers, is connected, 75 by means of links 15^g, with the end of an arm 21, the rear end of which is loosely mounted on the driving-shaft 22. This arm is connected, 80 by means of a link 21^a, with a crank on the main shaft.

Spring-bars 19, of which four are shown, are fixed at their upper ends, and they extend downward below the level of the table 85 18, upon which the marked letters are to be deposited. Their lower ends are connected by a cross-bar 19^a. These bars 19 occupy normally a substantially vertical position; but they are moved outward through slots 18^a in 90 the table against the marked letters, so as to cause the pack to be moved along the table, by means of two cams 20, which are pivoted to the fixed framework and are caused to rock into contact with two of the bars 19, whereby 95 to cause said movement of all of said spring-bars by means of links 20^a, through which they are connected with an arm 14^b, forming a part of the frame 14. Just before the lower edge of the letter which is being moved downward reaches the top of the marked letters 100 these spring-bars 19 are permitted to resume their normal position, whereby the letter is allowed to be moved down to the position referred to. As soon as the fingers have released this letter these spring-bars are moved forward by the cam, and this letter, as well as the others in the marked pack, are moved so that it does not in any wise interfere with the upward movement of the segregating-fingers. The marked letters are held in an 105 upright position by the sliding block 32, which rests upon the table 18.

Set in an opening in the plate 3^a is a movable plate 23, having downwardly-pointed spurs 23^a on its front face, which are adapted to engage with the foremost letter in the unmarked pack. This plate has an up-and-down movement, and through this movement it acts to move the foremost letter down upon 115 the supporting-table. The back side of this plate rests against the rock-shaft 7, which is flattened on one side, and its upper end is connected to a link 23^b, which is capable of moving endwise in suitable guides. This link is 120 connected with an arm 24^b, attached to a rock-shaft 24. Another arm 24^a of this rock-shaft is connected with an endwise-movable rod 24^c, which passes through a bracket 3^a, and a spring 24^d, compressed between this bracket and a 125 collar 24^e on the rod, acts to move the rod downward, whereby the rock-shaft is rocked in one direction. A cam 12^b on the disk 12 engages with a pin 24^g on the end of this rod and

periodically moves it in the contrary direction, and thus the plate is moved up and down once during each revolution of the shaft. During its upward movement it engages with the flat side of the rock-shaft 7^b, and thereby falls back into the recess in the plate 3^a and out of contact with the letter; but when it is moving down this shaft is turned and, acting like a cam on a plate 23, moves it toward and against the letter. One of the rollers 8^a over which the inking-belt passes has a ratchet 8^k on its outer end, and a pawl 8^m engages with this ratchet, which pawl is carried by an upwardly-extended arm 14^k of the swinging frame 14. Every time this frame 14 is moved backward and forward the inking-roller will be moved forward, thereby moving the inking-belt. The longitudinally-oscillating bars 2^a, upon which the pack of unmarked letters rests, are caused to oscillate by means of a rock-shaft 33, mounted beneath the table, and arms 33^a, secured thereto, which enter notches 2^c in the bars, and this rock-shaft is caused to rock periodically by means of a link 33^b, connecting an arm 33^c on said rock-shaft with the upper end of the push-rod 7^d.

The pins 4, which restrain the lower edges of the letters in the unmarked pack from springing toward the printing-block, are secured to arms 4^c, which are themselves secured to the rock-shaft 4^b, mounted on the under side of the table. An arm 4^c, secured to this rock-shaft, has a link 4^d connected to it, which link is guided so as to move endwise only, and it has a laterally-extended pin 4^e, which enters a cam-groove 30^b in the disk 30.

The machine is provided with means which act automatically to stop the feeding of the letters to the action of the marking and segregating devices in case a letter should not after it is marked be carried down by the segregating-fingers. A rock-shaft 35 is pivoted to the under side of the table 2, and to it are attached a plurality of curved fingers 35^a, capable of being swung up in front of the foremost letter in the unmarked pack. An arm 35^b on this rock-shaft is connected by a link 35^c with a block 36, having two notches 36^a 36^b, by which it may be hung from the rear end of the table. These notches are of different depth, as shown, and when the block is hung by the lower notch the rock-shaft is necessarily in such position as to hold said curved fingers downward below the level of the table. If a letter should accidentally get between the ends of these fingers and the arms which carry the needles, the latter arms will push the letter against these curved fingers, thereby rocking the rock-shaft, and this movement of the rock-shaft, transmitted through the link will push this block rearward until it falls and its upper notch engages with the end of said table. These fingers are now held in a position which prevents the letters from moving forward to the marking and segregating devices. These fingers are in this

position when a pack of unmarked letters is placed upon the table preparatory to the operation of the machine. This block 36 must be drawn rearward and upward until its lower notch engages with the end of the table before the marking and segregating of the letters begin. Secured to the top of the table near its lower end are two sliding bars 37, which serve as extensions of the table, and they also prevent the letters from engaging with said fingers when the fingers are down, as shown in Fig. 3. These bars are pushed back when the fingers are swung up by the pressure of a letter against their ends, but they automatically resume their normal position under the influence of the springs 37^a when the pressure upon them is relieved.

The partial vacuum in the recess in the marking-block 5, which causes the letters to be printed, may be produced by a vacuum-pump substantially like that which is shown in the drawings, and particularly in Figs. 15 and 16. The pump consists of a cylinder 40, having an intake-opening 40^a, with which the flexible pipe 6^a is connected. The piston 40^b of this pump is connected by a connecting-rod 40^c to a crank on the main shaft. A hole 40^d is made vertically through the piston-head and a vertically-movable valve 40^e is provided for closing this hole. The valve is normally closed by the action of a spring 40^f. The valve-stem 40^g, however, projects some distance below the piston-head and is in a position where it will be engaged by a toe 40^h on the connecting-rod. In the cylinder are the relief-ports 40^k, which are placed below the intake-port 40^a. When the piston begins its downward movement, the marking-block 5 is being moved forward toward the foremost letter in the unmarked pack, and when said marking-block is close to that letter the piston passes below the intake-opening 40^a, whereupon air is suddenly drawn out of the recess in the block 5, thereby creating such a partial vacuum therein as causes the letter to be forced against the printing characters. Almost immediately thereafter the piston descends so as to open up the relief-port 40^k, whereupon the air rushes into the cylinder. The vacuum is relieved both in the cylinder and in the recess in block 5, and the letter is released. When the crank on the shaft passes the center preparatory to beginning its upward stroke, the toe 40^h on the connecting-rod strikes the stem of the valve 40^g and forces the valve upward, thereby opening a communication between the space above and the space below the piston, so that in moving up it does not compress any air above it. This vacuum-pump is capable of operating in the described manner to perform the functions just described; but any other means for producing a partial vacuum in the recess in the block 5 and for maintaining that partial vacuum for a sufficient length of time may be substituted for said pump.

Having described my invention, what I

claim, and desire to secure by Letters Patent, is—

1. In a mail-marking machine, the combination of a table for supporting a pack of unmarked letters, means for clamping the upper part of the unmarked pack, a marking device for marking the foremost letter in the pack, an independent device which takes hold of said foremost letter at its lower edge and bends said edge away from the unmarked pack, and a segregating device which engages with the bent lower edge of said letter, substantially as specified.

2. In a mail-marking machine the combination of a table for supporting a pack of unmarked letters, means for clamping the upper part of said pack, and means for marking the foremost letter in said pack, with a plurality of needles, means for moving said needles, first, upward to cause them to penetrate the foremost letter in the pack, then from the pack to bend said letter, then down whereby they are withdrawn from the letter and finally back to the original position, and means for maintaining the separation of said letter from the pack effected by said needles, substantially as specified.

3. In a mail-marking machine, the combination of a device for bending the foremost letter in the unmarked pack which consists of a rocking frame having arms, and a rocking support upon which said frame is mounted, with blocks pivoted to said arms and having beveled upper ends, needles secured to said blocks opposite the beveled ends thereof, and means for rocking said frame and its support, substantially as specified.

4. In a mail-marking machine a movable arm and block pivoted thereto and having a beveled upper end, a spring which opposes the movement of said block in one direction, and a needle secured to said block in the described relation to the beveled side thereof, and means for moving said arm, substantially as specified.

5. In a mail-marking machine, the combination of a swinging frame, a marking-block pivotedly secured thereto, and having a recess in its front side, a marking-plate secured in said recess, means for periodically creating a partial vacuum in said recess, mechanism for swinging said frame, an inking device, means for turning the block upon its supports in said frame whereby the printing-surface is presented automatically to the inking device, and to the foremost letter in the pack, substantially as specified.

6. In a mail-marking machine, the combination of a swinging frame, its operating mechanism, and an inking device, with a marking-block having a recess in its front face and having trunnions by which it is pivoted to said frame, one of said trunnions being tubular and communicating with said recess, a printing-plate secured in said recess, an air-pump, and a flexible connection between the air-pump and the tubular trunnion

with means for turning the block upon its trunnion while its supporting-frame is swinging, whereby the printing-face is presented alternately to the inking device and to the letter to be marked, substantially as specified.

7. In a mail-marking machine, the combination of a swinging frame and its operating mechanism, a marking-block pivotally connected with said swinging frame and having a rearwardly-extended arm, a recess in its front face, and a marking-plate secured in said recess, with means for periodically producing a partial vacuum in said recess, a fixed track with which said arm engages, means for holding said arm against said track, and an inking device, substantially as specified.

8. In a mail-marking machine, the combination of a swinging frame having two depending arms, a pneumatic marking-block pivotally connected with said arms, an arm secured to said marking-block, a fixed track with which said arm is adapted to engage, a link pivotally connected with said arm, and a spring which acts constantly on said link whereby the arm is against said track, substantially as specified.

9. In a mail-marking machine the combination of a table for supporting a pack of unmarked letters, means for marking the foremost letter in the pack, means for bending the lower edge of this letter away from the unmarked pack, and a table for receiving the marked letters, with a vertically-movable head carrying fixed and movable fingers, a rock-shaft to which all of said movable fingers are secured, a spring or springs for closing said fingers, an arm on the rock-shaft, a rocking block adapted to engage with said arm to open said fingers and means for operating said block, substantially as specified.

10. In a mail-marking machine the combination of a vertically-movable head having a plurality of fixed fingers, mechanism for moving said head up and down, a rock-shaft mounted in said head, fingers carried thereby, a spring or springs acting to close said fingers against the fixed fingers, an arm secured to said rock-shaft, a rocking block engaging with said arm, and means for operating said block, substantially as specified.

11. In a mail-marking machine the combination of a table for supporting a pack of unmarked letters, means for marking the foremost letter in the pack and for bending its lower edge away from the pack, a vertically-movable device adapted to grasp the bent letter and segregate it from the unmarked pack, a table upon which said letter is delivered, and mechanism for moving the marked letters along said table, substantially as specified.

12. In a mail-marking machine, the combination of mechanism for marking and segregating letters from an unmarked pack, a table upon which said letters are delivered, a spring-frame, a cam which may press said frame against the marked letters, and a pivoted link

connecting said cam with the segregating mechanism, substantially as specified.

13. In a mail-marking machine the combination of a table for supporting a pack of un-

5 marked letters, means for clamping the upper part of said pack, mechanism for marking the foremost letter and for bending its lower edge away from the pack, with a plurality of pins adapted to be moved up and down 10 through the table into engagement with the lower edge of the unmarked letters thereon behind the foremost letter, substantially as specified.

14. In a mail-marking machine, the combination of a table for supporting an unmarked pack of letters, a marking device, and movable needles adapted to penetrate the lower edge of the foremost letter in the unmarked pack and to bend said letter to effect its partial segregation from the pack, and means to force the foremost letter down upon the supporting-table, substantially as specified.

15. In a mail-marking machine, a support for a pack of unmarked letters, a marking device, and movable needles adapted to penetrate the edge of the foremost letter and to bend said letter to effect its partial segregation from the pack, a plate having spurs which has a reciprocating movement in front 30 of the foremost letter, and means for causing it to engage with said letter in its movement toward said support, substantially as specified.

16. In a mail-marking machine, means for segregating a marked letter from the unmarked pack, and automatic means for ar-

resting the marking operation, said automatic arrest being operated by a failure in the segregating mechanism, substantially as specified.

17. In a mail-marking machine, a table supporting an unmarked pack of letters, a rock-shaft, means connected therewith for arresting the feed movement of said pack, a crank on said rock-shaft, a rod pivoted thereto, 45 means allowing movement of said rod in one direction but locking it against return, substantially as specified.

18. In a mail-marking machine, a feed-table, a rock-shaft journaled therein, fingers carried 50 by said rock-shaft, a crank carried by said rock-shaft, a rod pivoted on said crank, a block rigidly connected to said rod, said block having notches the lower of which normally grasps said table, whereby a thrust of said 55 rod brings the said upper notch into contact with said table and locks said rod against return, substantially as specified.

19. In a mail-marking machine, a feed-table, a segregating-arm, a rock-shaft, fingers carried thereby, contiguous to said segregating-arm, whereby a letter caught between said arm and said fingers moves said rock-shaft, and means for locking said rock-shaft against return, substantially as specified.

In testimony whereof I hereunto affix my signature in the presence of two witnesses.

EDWARD CHESHIRE.

Witnesses:

E. L. THURSTON,
ALBERT H. BATES.
